UNITED STATES PATENT OFFICE

2,363,349

ELECTRON DISCHARGE CIRCUIT

William W. Moe, Stratford, Conn., assignor to
General Electric Company, a corporation of
New York

Application April 24, 1942, Serial No. 440,313

4 Claims. (Cl. 250—36)

My invention relates to electron discharge circuits, and more particularly to oscillating circuits incorporating electron discharge devices.

Certain types of oscillating circuits, in which electron discharge devices are used as the driving elements and in which the operating bias for such devices is produced by their own oscillation, tend to oscillate intermittently. That is, the oscillating circuit operates at its normal frequency for a short period of time during which an excessive operating bias for the electron discharge device is built up, such bias being of sufficient magnitude to stop operation of the oscillator. After the operation at normal frequency stops, the electron discharge device being simultaneously stopped from producing its own operating bias, the excessive operating bias is gradually reduced to a point at which normal operation can be resumed. Such intermittent operation of an oscillating circuit is commonly termed blocked oscillation.

Such blocked oscillation is generally encountered in oscillators in which the operating bias is produced by grid rectification of the oscillations across a resistance in circuit between grid and cathode of the electron discharge device, the resistance being of too high a value. However, when certain oscillating circuits are operated at ultra high frequencies, of the order of from 500 to 3,000 megacycles and higher, such blocked oscillations are produced even though the resistance across which the operating bias is produced is of relatively small value.

It is an object of my invention to provide a new and improved oscillating circuit, in which the tendency to produce such blocked oscillations is minimized. It is a corollary object of my invention to produce such an oscillator circuit in which the tendency to produce excessive operating bias potentials is minimized.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 represents one embodiment of my invention, and Fig. 2 represents a modification thereof.

In Fig. 1, one end of a tuned circuit 10 is connected to the grid 11 of an electron discharge device 12, whose cathode 15 is grounded. The other end of the tuned circuit 10 is connected through a condenser 13 to the anode 14 of the

device 12. The potential of the cathode 15 of the device 12 is maintained intermediate the potentials of the ends of the tuned circuit 10 by a second tuned circuit 16, which is coupled in suitable manner, as by induction, to the tuned circuit 10 and which is connected between the control electrode 11 and cathode 15 through a condenser 17.

Operating current is supplied to the discharge device 12 from a source of potential (not shown) whose negative terminal is connected to ground and whose positive terminal is connected through a large inductance 21 and through a small inductance 18 to the anode 14 of the device 12. Bias potential for the control electrode 11 is developed across a suitable resistance 19 connected between ground and that end of the tuned circuit 16 opposite to the control electrode 11.

It may be found that the oscillating circuit, with all constants adjusted to desired values, tends to produce blocked oscillations described previously. This may be true at ultra high frequencies, even though the resistance 19 is of relatively small value. In such cases, a condenser 20 is connected from a point between the inductances 21 and 18 to a point between the resistance 19 and the tuned circuit 16. The inductance 18 is just sufficiently large to present a high reactance to current of the frequency to which the circuits 10 and 16 are tuned, while presenting substantially no reactance to current of the frequency at which the oscillating circuit tends to block. The inductance 21 is of much higher value, and presents a large reactance to current of the frequency at which the oscillating circuit tends to block. The condenser 20 is of sufficient capacity to present small reactance to current of the frequency at which the oscillating circuit tends to block.

In operation, with the discharge device 12 producing oscillations in the tuned circuits 10 and 16, whenever the oscillating circuit tends to block, the anode current of the device 12 tends to become smaller and, though the condenser 20, consequently reduces the excessive bias potential developed across resistance 19. This operation takes place in the following manner. When, for any reason, the bias potential developed across the resistance 19 tends to become excessively large, thereby making the control electrode 11 so negative in potential as to reduce the discharge current flowing through the device 12, the current through the large inductance 21 is decreased, and the potential drop thereacross correspondingly reduced. The potential of the point

between inductances 21 and 18 to which condenser 20 is connected therefore becomes more positive in potential, and by virtue of the coupling through the condenser 20, the ungrounded terminal of the resistance 19 is forced to become more positive. That is, the ungrounded terminal of the resistance 19, which, during the blocking action of the oscillating circuit, became highly negative in potential, is made to become less negative in potential. Since the blocking action of the oscillating circuit is due to the production of an excessively large bias potential across the resistance 19, such reduction of this bias potential through the coupling of the resistance 20 is effective to minimize, and in fact substantially eliminate, such blocking action.

The condenser 17, which is connected between one end of the tuned circuit 16 and the cathode 15 to provide a low impedance path therebetween at the frequency of oscillations, must have a low reactance at such frequency. However, this condenser 17 must have substantial reactance at the frequency of the blocking action which it is desired to suppress. Otherwise, voltage of the frequency of the blocking action appearing across the inductance 21 could not be impressed across the resistance 19 through condenser 20.

Viewed in another fashion, the action of the inductance 21 and condenser 20 in preventing such blocking action is to produce degenerative feedback from the anode circuit to the control electrode circuit of the oscillator, such feedback being effective only at the frequency of the blocking action and being sufficient in magnitude to prevent such blocking action. That is, the inductance 18, terminated by the condensers 20 and 17, forms a low pass filter which prevents transmission of the high frequency oscillating current from the anode 14 to the resistance 19, but which impresses across the inductance 21, and consequently across the resistance 19 because of the high reactance of condenser 17 and the low reactance of condenser 20 at such frequency, the voltage on the anode 14 of the blocking frequency.

It is understood that the inductance 21 may be replaced by a resistance, if desired, although an inductance is preferred to minimize power loss therein.

In a particular circuit in which this arrangement was utilized to prevent blocking of the oscillations, the tuned circuits 10 and 16 and the device 12 were arranged to operate at frequencies above 3,000 megacycles. The resistance 19 was made 12,000 ohms, condenser 20 was made 2,000 micromicrofarads, and the inductance 21 was made 16 millihenries. Without the inductance 21 and condenser 20, blocking in the oscillating circuit was very severe, but when the inductance and condenser were added was entirely eliminated.

The arrangement for eliminating such blocking action may obviously be utilized in any form of oscillator subject to such action, suitable means being utilized in the oscillator to obtain an alternating voltage of the frequency of the blocking action, together with means for impressing this voltage on the resistance across which the bias potential for the control electrode is developed, such alternating voltage being impressed thereacross in such phase as substantially to eliminate the blocking action.

Fig. 2 illustrates a different type of oscillator comprising somewhat different means for impressing alternating voltage of the frequency of

the blocking action on the control electrode of the oscillator in such phase as substantially to eliminate the blocking action. In this figure the electron discharge device 12 is similar to the device 12 in Fig. 1, and like reference numerals are applied to like parts thereof.

A tuned frequency determining circuit including an inductance 30, and a condenser 31 connected in parallel thereto, is connected at one end to the anode 14 and at the other end through a condenser 32 to the control electrode 11. An intermediate tap 33 on the inductance 30 is connected through a condenser 34 to the cathode 15.

Discharge current is supplied to the device 12 from a source 35 of operating potential therefor, the negative terminal of the source 35 being grounded. The current from the source 35 of potential flows through a circuit extending from the positive terminal of the source 35 through an inductance 36, intermediate tap 33 of inductance 30, the upper portion of inductance 30, anode 14, cathode 15, and ground back to the negative terminal of the source 35. The control electrode 11 is connected to ground and to the cathode 15 serially through a biasing resistance 37 and an inductance 38, which inductance is magnetically coupled with the inductance 36 as explained hereinafter.

In operation the oscillator operates in usual fashion, the cathode 15 being maintained at an alternating potential intermediate the potentials of the control electrode 11 and anode 14 by its connection through the condenser 34 to the intermediate tap 33 on inductance 30. The oscillations produced by the device 12 and the tuned circuits 30, 31 are effective to cause current rectification through the control electrode 11 and cathode 15 such that continuous current flows through the resistance 37, thereby developing a suitable biasing potential for control electrode 11.

In oscillators to which my invention may advantageously be applied, certain circumstances cause the operating bias developed across the resistance 37 to increase excessively, and to such values as to reduce the discharge current through the device 12 so much that oscillations produced by the device 12 and the tuned circuits 30, 31 cease, after which the bias potential across the resistance 37 disappears. This action results in intermittent bursts of oscillations, described previously as blocked oscillations.

The inductances 36 and 38 form a transformer whose action tends to prevent the blocking of oscillations produced by device 12 and the tuned circuits 30, 31. When an excessive bias potential begins to be developed across resistance 37, the discharge current through device 12 begins to decrease, causing a decrease in current flow through the inductance 36. This change in current flow through inductance 36 causes a corresponding potential to appear across the inductance 38, which is so poled as to cause the control electrode 11 to become less negative, or more positive, in potential. This action of the transformer 36, 38 in opposing excessive increases in bias potential produced across the resistance 37 is effective substantially to eliminate any blocking action of the oscillations produced by the device 12 and the tuned circuits 30, 31.

While I have shown and described a particular embodiment of my invention, it will be obvious to those skilled in the art that changes and modifications may be made without departing

from my invention in its broader aspects, and I, therefore, aim in the appended claims to cover all such changes and modifications as fall within the true spirit and scope of my invention.

What I claim as new and desire to secure by Letters Patent of the United States is:

1. In combination, an oscillating circuit including an electron discharge device having an anode, a cathode and a control electrode, means providing regenerative coupling between said anode and said control electrode to support oscillations, a resistance connected between said cathode and control electrode across which an operating bias potential for said control electrode is developed by reason of said oscillations, a source of operating potential, a discharge current circuit for said device including said source, said anode and said cathode, said device having a tendency to produce an excessive operating bias potential on said resistance resulting in intermittent blocking of oscillations in said oscillating circuit and simultaneous reduction of discharge current in said discharge current circuit, and means responsive to such reduction in discharge current for reducing excessive operating bias potential on said control electrode comprising a current conductive impedance in said discharge current circuit between said source of potential and said anode and a condenser connected from a point between said impedance and said anode to a point between said resistance and said control electrode.

2. In combination, an oscillating circuit comprising an electron discharge device having an anode, a cathode and a control electrode, means providing regenerative coupling between said anode and said control electrode to support oscillations, and a resistance connected in circuit between said control electrode and cathode across which operating bias potential for said control electrode is developed by reason of said oscillations, a source of operating potential, a discharge current circuit including said source, said anode and said cathode, said discharge device having a tendency to produce an excessive operating bias potential on said resistance with consequent reduction of discharge current through said device thereby producing a recurrent blocking of oscillations in said oscillating circuit and means for reducing such tendency comprising an inductance in said discharge current circuit between said source and said anode, and a condenser connected between a point between said inductance and anode and a point between said

resistance and control electrode, the reactance of said inductance being high and of said condenser being low at the frequency of blocking of said oscillations.

5. 3. In combination, an oscillating circuit including an electron discharge device having an anode, a cathode and a control electrode, regenerative coupling between said anode and said control electrode to support oscillations, a resistance connected between said control electrode and cathode across which an operating bias potential for said control electrode is developed by reason of said oscillations, a source of operating potential, a discharge current circuit including said source, said anode and said cathode, said discharge device being effective to maintain oscillations in said oscillating circuit and having a tendency toward blocking such oscillations by developing an excessive bias potential on said resistance, the discharge current in said discharge device being simultaneously reduced, and means for reducing the tendency toward blocking such oscillations comprising a current conductive impedance in said discharge circuit between said source and said anode, means for preventing said oscillations from appearing across said impedance and for producing a voltage across said impedance of the frequency of said blocking, and a condenser connected from a point between said impedance and said anode to a point between said resistance and said control electrode for reducing said excessive operating bias potential on said control electrode in response to voltage on said impedance of the frequency of said blocking.
4. In combination, an oscillating circuit including an electron discharge device having an anode, a cathode and a control electrode, means providing regenerative coupling between said anode and said control electrode to support oscillations, a resistance connected between said control electrode and said cathode across which operating bias potential for said control electrode is developed by reason of said oscillations, said discharge device having a tendency to produce an excessive negative bias potential across said resistance periodically to decrease the anode current of said device and to block said oscillations, and means responsive to said decrease of anode current for developing and supplying to said control electrode a potential opposed to said negative bias potential thereby to reduce said tendency to block said oscillations.

WILLIAM W. MOE.
